UNITED STATES PATENT OFFICE.

PETER G. WING, OF CHICAGO, ILLINOIS.

DESIGN FOR A TOY SAFE.

No. 38,810.

Specification for Design.

Patented Sept. 17, 1907.

Application filed August 15, 1907. Serial No. 388,739. Term of patent 7 years.

To all whom it may concern:

Be it known that I, PETER G. WING, a citizen of the United States, residing at Chicago, in the county of Cook and State of Illinois, have invented a new, original, and ornamental Design for a Toy Safe, of which the following is a specification, reference being had to the accompanying drawing, forming a part thereof.

The figure is a perspective view of a toy safe showing my new design.

I claim:

The ornamental design for a toy safe as shown.

PETER G. WING.
